UNITED STATES PATENT OFFICE.

GEOERGE KINGSTON, OF KOKOMO, INDIANA.

CARBURETER.

1,130,981.

Specification of Letters Patent. Patented Mar. 9, 1915.

Application filed October 13, 1913. Serial No. 794,825.

To all whom it may concern:

Be it known that I, GEORGE KINGSTON, a citizen of the United States of America, residing at Kokomo, in the county of Howard 5 and State of Indiana, have invented certain new and useful Improvements in Carbureters, of which the following is a specification, reference being had therein to the accompanying drawings.

10 This invention relates to improvements in devices for supplying explosive charges to internal combustion engines, and more particularly to carbureters especially adapted for use upon vehicles and other motors 15 where there is a constantly varying speed and load.

The object of this invention is to provide an automatic proportionate regulation of air and fuel whereby the most efficient operation 20 of a motor at all speeds and easy starting is effected.

A further object is to provide a simple construction which is cheap to manufacture and embodies certain other new and useful 25 features, all as hereinafter more fully described.

Having these and other ends in view, the invention consists in bringing certain old and well known elements into a new and definite 30 relation and combination within a suitable structure, whereby an automatic variation in the velocity of air passing over a regulable fuel supply is secured to give an explosive mixture which will be varied according to engine requirements and whereby 35 fuel is supplied in such a manner as to give a rich mixture in starting the engine and certain other new and useful features are provided all as hereinafter more fully described, reference being had to the accompanying 40 drawings in which—

Figure 1 is a longitudinal vertical section through a device embodying the invention; Fig. 2, a horizontal section through the same 45 substantially upon the line $x-x$ of Fig. 1; and Fig. 3 is an end elevation, with portions broken away and in section to show the construction.

It is common to construct carbureters 50 with a main air passage into which fuel is introduced and taken up by the air passing therethrough, the supply of fuel being controlled by a float within a float chamber and the outlet from the passage being controlled 55 by a throttle valve, but it has been found

that the desired proportion of fuel to that of air is not obtained at all speeds of the engine, due to the fact that the velocity of the air passing the fuel supply is not high enough at all times and is not automatically controlled. What are commonly known as "mixing valves" have also been used to supply explosive charges to internal combustion engines but in these devices, the fuel is admitted to the air passage by the lifting of a suction actuated member or valve and this member can not be arranged to accurately control the flow of fuel where the speed and load varies through wide ranges.

In this invention, certain old and well known elements, including a suction actuated valve, are brought into a new and definite relation, said valve being arranged to control the velocity of the air passing over the fuel supply and to control the suction acting upon a fuel by-pass to supplement the charges passing said valve. This arrangement is embodied in a structure shown in a preferred form in the accompanying drawings, in which a suitable cup-shaped float chamber 1 has a lateral extension 2 within which is located a valve seat for a valve 3 controlling the admission of fuel through a hollow stem 4 to the float chamber. The float 5 which is of the ring type operates through the medium of a lever 6 to unseat the valve and maintain the desired height of fuel in the chamber, the parts being all arranged and constructed in an old and well known manner. The open top of the float chamber is closed by a cover plate 7 which is formed with a leg or boss 8 extending downwardly in the center of the chamber and is provided with a screw-threaded lower end to engage an opening in the bottom of the chamber or cup. A nut 9 engaging the projecting end of the leg, forces the cup against a suitable packing 10 which is seated against a flange on the leg to prevent leakage and also holds the rim of the cup in firm contact with the cover plate. A passage, preferably formed integral with the cover, extends diametrically across the same and has tubular ends projecting laterally from the cover to one of which ends a pipe or conduit, (not shown) may be attached to conduct air into the inlet end portion 11 of the passage and to the other or outlet end portion 12 of the passage a pipe or engine manifold (not shown) 116

2

may be secured for conveying the explosive charges from the carbureter to an engine. A wall 13 extends transversely across the passage intermediate its ends and a continuation of the inlet end of the passage dips down beneath this wall forming a fuel supply chamber 14 the bottom of which is below the normal level of the fuel in the float chamber. This chamber is connected with 5 the float chamber by means of a duct or passage 15 formed in the leg 8, said duct opening through the bottom of the chamber 14 in the central portion thereof and being enlarged near its upper end to receive a needle valve 16 and to form a seat for said valve. The wall 13 is extended laterally to form a horizontal wall 17 over the chamber 14 and separate said chamber from the outlet end of the passage, the inner end of 10 15 20 25 30 35 40 45 50 55 60 65 70 75 80 85 90 95 100 105 110 115 120 125

the outlet portion of the passage adjacent to the wall 13 and above the wall 17 forming a suction chamber 18. In the wall 17 is an opening 19 closed by a ball valve 20 seating therein within the suction chamber, said ball being adapted to be raised by a partial vacuum created in the suction chamber by the operation of the pistons of an engine connected to the outlet end of the passage. Said ball is limited in its upward movement by a stop plug 21 screwed into an opening in the wall of the chamber 18 directly above the ball seat, and the suction in said chamber is controlled to regulate the speed and power of the engine, by a throttle valve 22 of the usual form, placed within the outlet end of the passage and operated by the usual lever 23 upon one end of a shaft to which the valve is secured.

Within the wall 17 between the opening 19 and upwardly extending portion 13 of the wall, is a screwthreaded opening to receive a tube 24 having notches 25 in its upper end to be engaged by a suitable tool for turning the tube to adjust its lower open end toward or from the bottom of the chamber 14, and open end of the fuel dust 15 therein. The needle valve 16 extends upward through said tube and is provided with the usual enlarged and screwthreaded outer end portion to engage the screwthreaded bore of a suitable boss 26 on the wall of the chamber 18, said boss being externally provided with screwthreaded on its outer end to receive a packing nut 27.

When the engine to which the carbureter is connected is at rest, fuel will rise in the duct 15 and overflow into the bottom of the fuel chamber 14, forming a shallow puddle therein, and the tube 24 will preferably be so adjusted that its lower open end will be in proximity to the surface of the puddle. When the engine is turned over in starting, there will be a strong suction through the tube 24 due to the fact that the gravity ball valve 20 is seated at the time. As the lower end of the by-pass tube 24 is close to the surface of the fuel puddle, the air drawn in over the fuel surface will take up a quantity of the fuel sufficient to form a saturated charge for starting the engine, and by adjusting the tube toward or from the fuel a greater or lesser proportion of fuel will be drawn through and easy starting of the engine is secured at all temperatures. The size of the by-pass 24 and the weight of the valve 20 are so proportioned relative to each other and to the piston displacement of the engine to which the carbureter is adapted to be attached, that as soon as the engine starts, the suction within the suction chamber 18 will lift the valve from its seat even when the throttle valve 22 is nearly closed and air will enter and mix with the charges drawn through the by-pass. The air passing the automatic gravity valve will always have a high velocity owing to the automatic choking of the flow by the valve at all speeds of the engine, and thus, owing to its velocity, the main body of air sweeping over the fuel supply will take up a quantity of the fuel to supplement that drawn in through the by-pass. The stop 21 is so arranged, that the ball valve cannot get out of place and it is also limited in its lift thereby so that at highest speeds, the passage will be somewhat restricted and cause a suction on the by-pass tube, the ball operating to constantly vary this suction as the speed of the engine varies. The ball valve also operates to constantly vary the air restriction or passage past its seat, and thus the velocity of the charges or air waves through the chamber 14 is maintained at such a height as to cause fuel to be taken up thereby, the checking of the flow of air through said chamber between impulses also causing a complete and thorough carburetion of the air.

In cold weather, if found desirable, the by-pass tube 24 may be set so that its lower end will be immersed in the fuel puddle when the engine is idle, and thus in starting raw gasoline will be sucked in through said tube and during the normal running of the engine a stronger suction upon the fuel supply will be secured through the by-pass.

Obviously, the form and arrangement of the parts, the construction and arrangement of the main air passage, and the particular manner in which the fuel is supplied thereto, may be varied without departing from the spirit of my invention, and further, any form of suction actuated valve may be substituted for the gravity ball valve if found desirable. I do not therefore limit myself to the construction shown.

Having thus fully described my invention what I claim is:

1. In a carbureter, the combination of a float chamber, a float in said chamber, a

- member formed with a passage formed intermediate its ends with a portion extending below the normal level of fuel in the fuel chamber and communicating with said float chamber to form a fuel puddle therein, a suction actuated valve in said passage, and an auxiliary passage opening at one end into said passage adjacent to the fuel puddle and at its opposite end into the passage at the 10 opposite side of the valve.
2. In a carbureter, the combination of a member provided with a passage extending therethrough, means for supplying fuel to said passage, a suction actuated valve to close said passage, and a by-pass member extending past said valve with one end opening adjacent to the fuel supply and its opposite end opening into said passage at the other side of said valve.
- 20 3. In a carbureter, the combination of a member forming a main air passage, a wall extending across said passage and provided with an opening, a suction actuated valve to close said opening, means for supplying fuel to said passage, and a tubular member forming a by-pass around said valve with an open end adjacent to and adjustable toward and from said fuel supplying means.
4. In a carbureter, the combination of a member forming a main air passage, a float chamber, a float in said chamber, means communicating with the float chamber to receive fuel therefrom and opening into said passage, a suction actuated valve in said passage for closing the same, and a by-pass around said valve opening at its ends into said passage at each side of said valve with one end adjacent to and adjustable toward and from said fuel supply means.
- 30 5. In a carbureter, the combination of a member forming a main air passage, a wall extending across said passage intermediate its ends and provided with an opening forming a valve seat, a suction actuated valve engaging said seat, means for supplying fuel to the passage at the inlet side of said valve, and a by-pass comprising a tubular member
- extending through said wall and adjustable therethrough.
6. In a carbureter, the combination of a float chamber, a float in said chamber, a member forming an air passage with a portion of said passage extending downward in said chamber below the normal level of fuel in said chamber and provided with a duct 55 communicating with the float chamber and opening into the bottom of said portion of the passage, a wall extending across said passage adjacent to said portion and provided with a screwthreaded opening and an 60 opening forming a valve seat, a valve engaging said seat, and a tubular member in said screwthreaded opening to be adjusted therein toward and from the bottom of said portion of said passage.
- 65 7. In a carbureter, the combination of a float chamber, a float in said chamber, a member forming a cover for said float chamber and formed with an air passage extending across the same and downward intermediate its ends into the float chamber below the normal level of fuel therein to form a fuel chamber, said member being provided with a duct communicating with the float chamber and opening into the bottom of the 70 fuel chamber, a wall extending across said passage above said fuel chamber and provided with an opening to provide communication between said fuel chamber and the outlet end of the passage, a suction actuated 75 valve to close said opening, a tubular member extending through said wall with its lower end adjacent to said duct, a needle valve for controlling said duct extending upward through said tubular member, and a 80 throttle valve in the outlet end of said passage.
- 85 In testimony whereof I affix my signature in presence of two witnesses.

GEORGE KINGSTON.
